UNITED STATES PATENT OFFICE.

FREDERICK HEATH, OF TACOMA, WASHINGTON.

LINTEL.

1,244,328.

Specification of Letters Patent. Patented Oct. 23, 1917.

Application filed June 9, 1916. Serial No. 102,634.

To all whom it may concern:

Be it known that I, FREDERICK HEATH, a citizen of the United States, and a resident of Tacoma, in the county of Pierce and State of Washington, have invented a certain new and useful Improvement in Lintels, of which the following is a specification.

My invention relates to improvements in lintel constructions, and it consists in the combinations and arrangements herein described and claimed.

An object of my invention is to provide lintels which may be made in varying sizes by the use of hollow blocks, these blocks being the same as those which are used in building hollow walls.

A further object of my invention is to provide a lintel construction, built of hollow blocks, in which lintels of various widths may be built, without the necessity of using additional forms of blocks.

A further object of my invention is to provide a lintel construction in which the blocks forming the lintel are not only joined together longitudinally by means of reinforcing rods, but are also locked together laterally by the same rods.

Other objects and advantages will appear in the following specification, and the novel features of the invention will be particularly pointed out in the appended claims.

My invention is illustrated in the accompanying drawings, forming part of this application, in which—

Figure 1 is a perspective view of a lintel formed from a single row of blocks.

Fig. 2 is a section through a modified form, showing a wider lintel, in which two rows of blocks are used.

Fig. 3 is a diagrammatical plan view on a reduced scale of the lintel shown in Fig. 2.

Fig. 4 is a view similar to Fig. 3, showing another modified form, in which the lintel is a still greater width.

Fig. 5 is a section along the line 5—5 of Fig. 3, and

Fig. 6 is a section along the line 6—6 of Fig. 3.

In carrying out my invention, I make use of hollow blocks. In Fig. 1 the block is shown in general at A. It will be noted that the block has a central void B and on either side of the central void larger voids which in the illustration are shown as filled with

concrete C. These blocks without the concrete filling are the same as are used in making hollow walls and in connection with them I use a block D, see Fig. 5, having a central void, which in Fig. 5 is shown as 60 filled with concrete C.

The blocks A and D are used together when building lintels of, say, greater width than eight inches. I may, however, make the lintel entirely of the blocks A. In Fig. 65 1, the lintel as shown is made up of a series of blocks A, laid end to end. In preparing the lintel, these blocks A are preferably laid vertically, one on top of the other. Reinforcing rods R are then placed in position 70 in the side voids, near that wall which will be the bottom of the finished lintel, and then plastic concrete C is poured into the larger side voids until these voids have been 75 completely filled. It will be understood, of course, that the joints between the blocks are filled with mortar.

Now, when the concrete has set, the lintel will be held together firmly and can be used as a unitary structure. The lintel is 80 joined together laterally as well as longitudinally, owing to the reinforcing rods R. In making a wider lintel, I use, as stated, the block D in conjunction with the block A. As will be seen from Fig. 2, the blocks 85 D and A are staggered, or considering one row, the blocks A and D alternate. The reinforcing rods R, in this instance, are placed so that the rod which passes through one of the voids of the three-void block, 90 also passes through the single void of the adjacent block at either end. Now, when the concrete is poured in and allowed to set, this will form a lintel in which the reinforcing rods R not only bind the structure together longitudinally, but also laterally, thus obviating the necessity of the use of additional binding means.

In Fig. 4, I have shown a further modification, in which one section of the lintel 100 consists of two three-void blocks, the adjacent section consisting of one three-void and two one-void blocks. In this instance, as in the case shown in Figs. 3 and 5, rods pass through the voids in such a manner 105 that the structure is locked together laterally as well as longitudinally.

In Fig. 1, the outer surfaces of the block are shown as provided with corrugations E. These corrugations are omitted from the 110

diagrammatic views 3 and 4 for the sake of clearness, *i. e.*, to more clearly show the reinforcing rods.

It will be readily understood that there is considerable advantage in forming lintels in this manner. As stated before, the three-void blocks and the one-void blocks are used in making hollow walls and the same blocks may be used for the lintels. The fact that the lintels can be made of varying widths and still be joined together laterally as well as longitudinally is another feature. Lintels made in this manner are exceedingly strong and have the advantage that they can be made very readily by any one on the spot where they are to be used, thus obviating the necessity of transporting heavy lintels.

I claim:

20 1. In a lintel construction, a plurality of sections of hollow blocks laid end to end, alternate sections being identical in arrangement, and certain blocks of one section overlapping a plurality of blocks of adjacent sections, reinforcing rods running through said blocks and through the overlapping blocks at either end, and plastic

material filling said hollow blocks and embedding said rods.

2. In a lintel construction, a plurality of sections of hollow blocks laid end to end, alternate sections being identical in arrangement, certain blocks of one section each overlapping a plurality of blocks of adjacent sections, reinforcing rods passing through all of the overlapping sections longitudinally of the lintel, and plastic material filling said hollow blocks and embedding said rods.

3. In a lintel construction, a plurality of sections laid end to end, each section being composed of a plurality of hollow blocks, said blocks having one or more voids, the one-void blocks of any section registering at each end thereof with blocks in adjacent sections having a plurality of voids, reinforcing rods extending through said registering voids longitudinally of the lintel and concrete filling the voids containing the reinforcing rods and embedding the latter, and binding material between the joints at the ends of the adjacent blocks.

FREDERICK HEATH.
